UNITED STATES PATENT OFFICE.

STEPHEN D. CARPENTER, OF CARTHAGE, MISSOURI.

COMBINED PRINTING AND ADDRESSING MACHINERY.

SPECIFICATION forming part of Letters Patent No. 402,561, dated May 7, 1889.

Application filed April 28, 1888. Serial No. 272,142. (No model.)

To all whom it may concern:

Be it known that I, STEPHEN D. CARPENTER, a citizen of the United States, residing at Carthage, in the county of Jasper and State of Missouri, have invented and made certain Improvements in Combined Printing and Addressing Machinery, of which the following is such a full, clear, and exact description as will enable any person skilled in the art to make and use the same, reference being had to the accompanying drawings, forming a part of this specification.

The more definite objects of my invention are, first, to secure a self-feeding printing-machine suited to job and book work of various sizes and kinds; second, newspaper work, either folio, quarto, or other character; third, automatically placing subscribers' addresses on newspapers as printed; fourth, to print in two or more colors at the same operation on commercial job-work, newspaper or book printing. I attain these objects by mechanisms illustrated in the accompanying drawings, consisting of eight sheets, in which—

Figure 1 is a side elevation showing an end view and the arrangements of the various sets of cylinders. Fig. 2 is a side elevation of the printing sets of cylinders from the working side of the machine, showing the graduating sections on the cylinder. Fig. 3, Sheet 2, is a diagram showing the longitudinal markings of a form-cylinder, which, together with the dotted lines thereon indicating the lines of cutting, show how a variety of jobs of different sizes may be worked and cut at the same operation. Fig. 4, Sheet 2, is a diagram showing the longitudinal and cross markings and numberings of the graduated sections of the cylinders, for convenience in arranging colored work for one or more colors in newspapers. Fig. 5, Sheet 3, is a view showing the two form and two impression cylinders, including the inking devices and their appendages. Fig. 6, Sheet 4, is a plan view of parts shown in Fig. 5. Fig. 7, Sheet 5, is a front end elevation showing the form and impression cylinders, the manner of locking the "forms" or segmentary zinc or stereotype cylindrical plates on the form-cylinders, the frame, cross-pieces, &c. Fig. 8,

Sheet 6, is an end view of a portion of the cut-off cylinders. Figs. 8^A and 8^B are rear views of slats on the cut-off cylinders. Fig. 9, Sheet 6, is a longitudinal section of the cut-off cylinders, showing the construction of the sections of cut-off knives, spiral spring, locking devices, &c. Fig. 10, Sheet 6, is an enlarged view of a section of the system of knives; Fig. 10^A, a top view of the same, showing the manner of locking to the cutter-bar. Fig. 11, Sheet 1, is a side view of the revolving shears. Fig. 12, Sheet 1, is an edge view of the revolving shears mounted on bearings. Fig. 13, Sheet 1, is a view of the half-sections 65 of the circular cutter of the shears. Fig. 14, Sheet 7, is an end view of the addressing-cylinder, showing the web-spool, gumming and actuating rollers, trip-pin, cut-off, &c. Fig. 15, Sheet 7, shows the serrated shears for 70 cutting off the printed addresses from the scroll as they are drawn from the spool. Fig. 16, Sheet 7, is a side view of the addressing-cylinder, showing gumming-fountain, trip-pin, and operating mechanism. Fig. 17, 75 Sheet 3, is a plan view of one of the partitioned ink-fountains. Fig. 18 is an enlarged view of the addressing mechanism, and Fig. 19 is a plan view of bolt-locking cutter-bar in Fig. 10.

Similar letters and figures refer to similar 80 parts throughout the several views.

It requires one "set" or pair of cylinders to print upon paper—the type-bearing and the impression cylinder—and also a set or pair each for addressing subscribers' names 85 and cutting off the sheets. I therefore designate the cylinder sets by capital letters in Fig. 1 in the order they are to work, A, the addressing-cylinders, and B, first set of form and impression cylinders, being the same in construction with sets C D E F G, except in operation, for which the cylinders in sets C, E, and G are made reversible, so that only one or both sides of the paper may be printed at the same operation, as may be desired. 90

H is the cut-off set. All the cylinders roll together from the right, so as to draw the paper at a' from the web-roll, Fig. 1. g⁸, Fig. 7, represents a driving-pulley on the shaft of the lower cylinder for the purpose of giving such 100 rotation.

Fig. 2 is a side elevation of the form and

impression cylinders from the front or working side, showing the numeral graduations of the circumference of the cylinders and the position of the various divisions ready for 5 commencing work on jobs requiring, say, six colors, and this figure should be read in connection with Fig. 3, which is a diagram of the longitudinal plane of the cylinders and the longitudinal graduations thereof—as, for 10 example, suppose that Fig. 3 represents the poster to be printed, and that it is desired to print red color in numbers 1 and 7, black in numbers 2 and 8, blue in numbers 3 and 9, pink in numbers 4 and 10, green in numbers 15 5 and 11, and yellow in numbers 6 and 12; then set the cylinders so that the set B will print on sections 1 and 7, set C will print sections 2 and 8, and so on, and, as the distance between the vertical centers of the cylinders is exactly half the circumference of the cylinders on the "pitch-line," it follows that as the types in division 1 of B will print the first section on the bill, the types in section 7 will print a middle section of the poster, 20 while the half-revolution will have brought the space 2 on the cylinder in set C to fill the space 2 on the paper, and by the time the head of the sheet reaches the set D the set C will have printed 2 and 8, and set D is ready 25 to print in the spaces 3 and 9. Set E, having made one and one-half revolution, will print in the spaces 4 and 10, and so on to the finish and repeat. When the sheet has passed the set G, it may be slit up by the revolving 30 shears a^{40} , as shown in Fig. 1, and cross-cut by the cut-off knives in equal divisions or in unequal divisions, as may be desired.

Fig. 4 is a diagram showing both the longitudinal markings of the form-cylinder for 40 use and convenience in the insertion of colored work, such as cuts, maps, zincographic designs or transfers, or advertisements in newspapers. Say that a zincograph portrait, map, or an advertisement is to be inserted in the 45 middle of columns 4 and 5 of any given page. The foreman marks a printed diagram of the proper page, giving it to the stereotyper, zincographer, or etcher, as the character of the work may require, which is to receive, say, 50 four colors. If for letter-press work, the stereotyper sees at a glance how to arrange his print and blanks to fill the order, or the zinc-worker knows just on what part of the cylindrical segments to locate his work with- 55 out the trouble and delay of spacing off the cylinders to correspond with the blank left in the newspaper "forms," &c., and the work is duly arranged for each of the four cylinders carrying the proper colors, and so on for any 60 job, advertisement, or other matter, and the job or newspaper work may be almost indefinitely varied to suit almost any class of work. Each set of cylinders and accompanying ink-fountains and ink-distribution rollers 65 and cylinders, while distinct and independent of each other, yet act in unison to secure as perfect "register" as the tension strength

of the paper will permit, so that each alternate color may be deposited in the proper place thereon more perfect and accurate than 70 can be done by machines printing on sheets supplied by hand-feeding.

The usual system of damping and inking rollers and fountains is placed in combination with any set of cylinders that may carry 75 zincographic plates.

Fig. 5 is an enlarged view showing two sets of form and impression cylinders, F G, including the inking and ink-distribution devices and their appendages. As all the alternating form and impression cylinders are of exactly like construction and operation, this description will answer for and apply to every other alternate set or pair.

The intermediate gears, a^3 , Figs. 1, 2, and 85 5, engage with the cylinder-gears a for the sole purpose of giving a like motion—from right to left of the impression-cylinders and from left to right of the printing-cylinders a^4 .

For convenience in putting on and locking 90 the cylindrical stereotype or zinc plates, the frames are cut away above all the upper cylinders and below each set of reversible cylinders, Figs. 1 and 5. When the zinc or stereotype cylindrical plates are properly locked on 95 the cylinders, then the bracket roller-plates b^6 , Fig. 5, are bolted to place and the type-inking or form rollers b and the distribution-rollers c , Fig. 5, as well as the reciprocating rollers d , Figs. 5, 6, and 7, and the large distribution-rollers c' are put in place, the plates bolted on, and the brackets e , Fig. 5, adjusted with set-screws, so that the type-inking or form rollers may have the proper bearings on the face of the printing-surfaces and all the inking and 100 distribution rollers may have proper friction-bearing on each other and the form-cylinders.

c' are large distributing-rollers mounted separately with friction-bearing on the distributing and inking rollers. These rollers are 110 made in the usual way.

The cylinders a and a^4 , Figs. 1 and 5, are provided with adjustable boxes a^6 , for the purpose of regulating the impression.

The set of cylinders G, Fig. 5, as well as 115 sets C, E, and F, Fig. 1, are constructed so that the cylinders are reversible. They are journaled in the inside reversible frame a^5 , Figs. 1 and 5, and made to swing on the trunnions or journals a^8 , so that when it is necessary to print the sheet on both sides, either plain or in colors, the cylinders of each alternate set may be reversed, and the inking mechanism is so arranged that the lower fountains will supply the system of inking 120 and distribution rollers without further trouble.

Fig. 5 shows a system of inking and distribution rollers both above and below the G pair of cylinders; but the ink and distribution rollers are never to be used at the same time, and are only so drawn to show the actual positions and purposes when used in reverse order.

The type-inking rollers receive their motions by frictional contact with the printing-plates and likewise communicate motion to the distribution-rollers, all by friction in the usual manner.

The distributing reciprocating rollers, Figs. 5, 6, and 7, obtain their longitudinal motion from the arms a^9 , from the ends of which project pins or rollers between two plano-convex flanges affixed to the shanks of the reciprocating rollers b . These arms are made fast and keyed by a hub to the vertical rock-shaft a^{16} , which has two bearings bolted to the frame, and also has centrally-projecting arms a^{11} , which engage by connecting-rods a^{12} with another vertical rock-shaft for like purpose, and thus all the reciprocating rollers for each set of cylinders are operated, primarily, by the "wabble" or angular gear-wheel a^{13} , which is mounted on a short wrist or stud attached to the main frame and consists of an angular disk or wheel, pinion, and short stud. This wheel engages a pinion, a^{14} , on the shaft of the impression-cylinder a in series E, which reduces the motion as about one to three of said cylinder, so as not to give the roller a too sudden jerky motion. The face-disk of the reducing-wheel a^{13} is set at such angle to the wrist on which it moves as to give the reciprocating rollers d a lateral motion of some two inches to cut up and distribute any small masses of ink that may be transferred to the rollers, and their motion is secured by a cross-arm, a^{15} , keyed to the rock-shaft a^{16} , to which at each end, and bearing on the angular disk, are attached concave rollers that follow the angular plane of the wabble-disk and thus cause the shaft a^{16} to rock, and by the connecting-rod a^{12} the whole system of reciprocating rollers d on the press is worked, as shown in said Figs. 5, 6, and 7.

The ink-fountains a^{17} , Figs. 5, 6, and 7, are operated for each double set of cylinders by a cam, a^{18} , of such curve that the concentric part of the groove may hold the arm a^{20} in its outward position more than half its circumference and not remain long at the change. This cam-wheel engages with the outside pinion, a^{19} , Figs. 5 and 7, and reduces the motion as one to three of the impression-cylinder a in series E to avoid too rapid motion of the inking mechanism.

To operate the ink-fountains a^{17} , the cam-arm a^{20} , Fig. 5, is pivoted at a^{21} , and a roller affixed at its free end to move in the groove of the cam a^{18} receives the connecting-rods a^{23} and a^{24} at the connecting-joint a^{22} . The connecting-rod a^{23} connects with and operates the ratchet-arm of the lower ink-fountain, a^{25} , and the rod a^{24} , Fig. 5, connects with and operates the ratchet-arm a^{25} of the upper ink-fountains.

The ink-fountains are made substantially like the ink-fountains of the ordinary web-printing presses now in use, except that for convenience and economy of construction and operation, instead of providing mechanisms

for two motions to operate the ink-cylinder a^{26} , Figs. 5, 6, and 7, and the transfer-rollers, the two classes of mechanisms are practically reduced to one and substantially to one motion, viz: The ink-cylinder a^{26} is cast hollow, having its own journal-bearings, one end projecting sufficiently to receive the ratchet a^{27} , Fig. 5, and through these bearings and the entire length of the cylinder a^{26} is inserted a strong one-inch steel shaft projecting at each end, so as to receive the transfer-roller ratchet-arms a^{28} and a^{29} , the latter of which carries the pawl that operates the ink-fountain ratchet, and the other by its forked end holds and operates the transfer-roller a^{29} . As the cam a^{18} raises the connecting-rod a^{23} the ratchet-arm of the ink-fountain is also raised, and this, by the pawl acting on the ratchet, moves the ink-cylinder slightly, so that a fresh mass of ink is brought in contact with a transfer-roller, a^{29} , which takes off a small quantity of ink, and the same motion on reversal forces the transfer-roller against the revolving distribution-cylinder c' , Fig. 5, remaining in friction contact with that cylinder until its rapid motion has taken off the fresh ink from the fountain. As the transfer-roller works from the same center with the ink-cylinder, it would remain in contact therewith and fail to transfer the ink to cylinder c' except for the action of the "riser-cam" a^{30} , which bears against the shank of the transfer-roller, radiating sufficiently from the center of action to force the transfer-roller free from the ink-cylinder and in contact with the distributing-cylinder c' . The rod a^{31} , Fig. 5, connects the two ratchet-arms of the upper ink-fountain, so that a full set of three ink-fountains, that may be shifted or interchanged for other fountains containing other colors to suit the reversibility of the type and impression cylinders in each alternate set, are made to operate as desired by one set of mechanical devices all operated by one cam, as described.

All the other ink-fountains are made and operated as herein described, except that for special purposes I provide several extra ink-fountains, Fig. 17, Sheet 3, with one or more divisions and continuous ink-cylinders fitted ink-tight to the partitions for the purpose of using two or more colors, if desired, for one set of printing and impression cylinders for special color-display in certain kinds of job-work, which colors may be slightly blended, if so desired, or the reciprocating rollers may be unshipped, and thus avoid blending. Fig. 17, Sheet 3, represents one of these extra fountains, w being the partitions, and y the ink-cylinder. Otherwise the foregoing description applies to all the ink-fountains.

The reversible cylinders may be reversed by withdrawing the four bolts $o o i i$, Fig. 5, that secure the inside swinging frame to the outside frame, and replacing said bolts when the cylinders are in position, and for this purpose the bolts and holes should be made of the same size and relative position to center

of action. The intermediate gear, a^3 , nearest to the cylinder moved should be first removed from the wrists that hold them, and also the inking-rollers and the ink-roller plates, and then the reversible pair of cylinders will swing easily to place. When the bolts and intermediate gears are replaced, then the inking and distribution rollers may be set, and they are ready for work.

10 a^3 , Figs. 5 and 7, shows the hinged cover to ink-fountain.

a^3 is a clamp that is pivoted to the ends of the fountain-box, with right-angle projections at the top end, which, when swung around over the inclined cover of the fountain, forces upon the same and holds the cover to place to resist the force of the thumb-screws a^4 as they press upon the steel-sheet scraper under the cover a^3 , and bearing on the ink-cylinder 20 to regulate the flow of ink, in the usual way.

Fig. 6, the plan view, has already been generally described.

The front end elevation, Fig. 7, has been generally described herein, except the construction and operation of the printing-cylinders.

f^f , Figs. 1, 5, 6, and 7, show the outside frames, supported by the cross-braces g^7 , Fig. 7. The inside or swinging frame, into which 30 the reversible cylinders are journaled and which frame swings on the trunnions a^8 , Fig. 5, bearing on the outside frame, are represented by a^7 , Figs. 1, 5, 6, and 7.

a^4 represents the form-cylinders, and their 35 manner of construction is as follows: Being intended for job as well as newspaper work, I cannot have a double-beveled center lock permanently affixed to the center of the cylinder, as in web-presses designed exclusively for 40 newspaper work; but I make the permanent bevel lock-ring at the gear end of the cylinder g' . The skeleton size of the cylinder is turned one and a half inch in diameter less than the pitch-line, so as to receive the cylindrical zinc or stereotype printing-plates, made 45 three-fourths of an inch thick, and these bring the printing-surface up to the pitch-line. To firmly lock these cylindrical plates to the cylinder and leave nothing in the 50 longitudinal center of the cylinder to interfere permanently with the cylindrical plates for posters or other jobs, I make the gear-end lock-ring g' solid to the skeleton cylinder, as described, beveled inward, as per the dotted 55 line, about forty degrees. I then construct a steel bevel ring five-eighths of an inch in thickness and about two inches wide, beveled from the outside inwardly about forty degrees at both edges, and made to a free fit on 60 the skeleton cylinder. In printing newspapers or other work requiring a center margin this double lock-ring is placed in the center of the cylinder at the dotted lines, as shown, between the slots g^9 , Fig. 7. A second 65 loose steel locking-ring, g^3 , Fig. 7, is beveled only on the inside about forty degrees, as on the other rings, and about two inches wide

and five-eighths of an inch in thickness. If only some of the sets of cylinders are used, the web passes on and out between the others un- 70 acted upon in the usual way.

In case I desire to work jobs or book-work requiring the full printing-surface of the cylinder to be filled by continuous cylindrical stereotypes or zinc plates, I move the two 75 movable lock-rings to the working end of the cylinder, it being made long enough over all to receive them outside the maximum sheet of paper. These two rings are then practically used as one, as shown at $g^2 g^8$, Fig. 7. It 80 follows that either the one or both of these rings may be forced against the printing-forms or segment-plates by the movable head-blocks g^4 , the screws g^6 passing freely through the movable blocks, which project up through 85 the skeleton cylinder at the working end five-eighths of an inch above the skeleton surface of the cylinder, and the screws g^5 engage with the center piece, g^6 , which is threaded to receive them inside the cylinder. There are 90 four screws and movable head-blocks quadrilaterally located around the circle of the cylinder, so as to force the bevel locking-rings firmly on all sides against the printing-plates. The two beveled locking-rings are made suffi- 95 ciently free to enable one set of plates to be lightly held in place while the opposite plates are being inserted on the cylinder, and when all the printing-plates are thus inserted the screws and head-blocks should be firmly set 100 up, locking the plates in position.

The locking head-blocks should be shoul- 105 dered inside the projecting rims of the cylinder, so that they cannot rise up through the slotted openings. The ends bearing against the lock-rings may be faced even or beveled, so as to partly clamp over the outer edge of the locking-ring.

The slots g^9 in Fig. 1 are cast into the cylinder on opposite sides, to allow a piece of 110 wood or metal to be placed, firmly, against which the newspaper or other full cylinder forms may rest as a gage, so that when the forms are placed in position they will be in 115 register with corresponding forms.

The job or other segments, other than for 120 full pages for book or newspaper work, may be made of any desired width, covering a part of or one or more of the longitudinal or circumferential graduations of the form-cylinders, reaching, of course, the full length of the cylinders, and beveled, so as to be firmly held by the locking-rings—the part to be printed to be only in relief, no matter how large or small or on what part of the cylinder—the non- 125 printing part being some half-inch thick and made to fit the cylindrical surface of the form-cylinder, while the part in relief shall be "type high," or, say, three-fourths of an inch, so as to contact with the inking-rollers and to receive the film of the color desired, 130 and in all cases where polychromic printing may be desired the segments suited to each color are so placed alternately on each cylin-

der that when the last form is imprinted the work is complete, with all the colors placed chromatically as desired.

5 Figs. 8, 9, 10 and 10^a represent views of portions of the cut-off cylinder.

a, Fig. 8, and a⁴, Fig. 8, represent the set of cylinders shown in Fig. 1 as series H.

In Figs. 8 and 9, k represents an annular projection to receive and hold the guide-rods 10 k', that guide and support the knives and retain in place the spiral springs k². The outer shell or segmentary cylindrical slats, k³, project considerably beyond the guide-rods, which pass through both the projections and 15 are held by nuts at k'. (See Figs. 8^A and 8^B.) These guide-rods pass freely through a boss, k⁴, on the ends of the cutter-bars, to which is attached a roller, k⁵. This roller rises on 20 cams k⁶, Fig. 8, attached to each side of the frame, just before the cutting takes place, which force the lancet-pointed knives to withdraw within the circle of the cylinder-shell, and when at a vertical point over the center of the cylinder a, Fig. 8, (see letter H in 25 Fig. 1,) the cam k⁶ ends abruptly, allowing the whole series of knives for that section of the cylinder to descend with sufficient force to sever the sheet of paper. These series of knives are equidistant, according to the 30 length of the circumference of the cylinder, and their cumulative and changeable effects are further illustrated in diagram Fig. 3. The dotted lines on the diagram indicate the lines of cutting.

35 Arms k⁶, Fig. 8, project from the hub between each series of knives to support the cylindrical segments k³. As the knife drops off the riser-cam k⁶, it is forced down by its own weight and the spiral springs, and the 40 points pass the pitch-line of the cylinder a into a V recess, cutting the paper in the operation.

As it may often become necessary to cut the paper into unequal sizes, as shown in diagram Fig. 3, the knife-blades are divided 45 into sections, answering in length to the minimum width of the jobs which the press is intended to print—say four inches—taking care that the length of each section shall be 50 an aliquot part of the maximum width of sheets the press is intended to work. Supposing the maximum width of the paper to be forty-eight inches, the sections should be divided into twelve in number; and to provide 55 against a “poor start” of the paper into the machine, or a lateral variation by unequal tension or other cause, the outside sections should be five inches long, so as to secure a severance of the paper at any probable variation of the sheet.

To enable the pressman to place and replace the knife-sections at pleasure and with facility, the sections (excepting those on the outside) should be so exactly alike as to be interchangeable.

In the longitudinal center of the sections, and within three-eighths or one-half of an

inch of the back edges, a three-eighths-inch round hole should be punched, with an opening of half the diameter of the hole to the 70 edge opposite the cutting-edge, as seen in Fig.

10. The locking screw-bolt should have a large round flat head. The screw just fitted to the round hole l, Figs. 8 and 10, should be cut away at sharp angles close to the head 75 (see special view in Fig. 19) and wide enough to freely receive the steel cutting-blade, and the flattened part of the screw-shank l' should freely pass through the opening to the round hole l from the back edge of the blade. The 80 screw-head has a projection, at l², Fig. 10, where it is pivoted with the tilting bar l', Fig. 10, and firmly locked, and when this bar is thrown to the left ninety degrees to the point l³ the whole number of sections in the series will 85 become unlocked, and can be easily removed by the fingers. When the sections that are desired not to cut the paper shall have been removed, the tilting bar may be reversed and the remaining sections become firmly locked. 90

The sections are all to be pivoted to the tilting bar l', Figs. 9 and 10, which is provided with an eye, at l⁴, Fig. 9, and may be moved either to lock or unlock by inserting a hook in the eye. When it is desired not to use 95 any section in one or more of the series of knives, as in newspaper-work, &c., the cutter-bars may be pressed in toward the center of the cylinder, so as to permit the pin l¹⁰ to rest in the fork l⁵, Fig. 8, and the action of such 100 series of knives will be suspended. A back sectional view of the cutter-bar, screw-head, blade, and tilting bar will be seen at m, Fig. 10^a. The lancet-pointed cutting-edge of the blades should be serrated, as at n, Fig. 10, at 105 an angle of about forty degrees. The inner edges, points, and roots of the projections (which should be some one-fourth of an inch in length) should all be brought to thin edges and sharp points, not necessarily cutting-edges, but close and somewhat rounded edges, 110 so as to easily part, but not tear, the paper. It is important to have the points brought to a needle sharpness, so that they may easily and freely enter the paper.

115 When used for jobs or other than newspaper-work, and when the sheets may require to be slit longitudinally or kept taut by friction-rollers, the revolving cutters, Figs. 11, 12, and 13, are mounted on shafts and bolted to the frame, as shown at a⁶, Fig. 1, with the contact, cutting, and bearing edges in line with the web for slitting the paper as required, or without the cutting-knives, if cutting be not desired; but in any event these rollers 120 are to be used as friction-rollers for tension of the web in conjunction with the bite or friction of the cut-off cylinders.

125 Figs. 14, 15, and 16 represent the addressing mechanism for automatically affixing subscribers' addresses to newspapers. Fig. 14 is an end view of the upper cylinder in the set, designated A in Fig. 1. The cylinder consists of two cast disks or end pieces with hubs, for

the purpose of keying to the shaft, which 5 disks are connected by some sheet metal to form a cylindrical surface, on which the paper bears evenly as it comes from the roll, and the cylinder should be of equal length of the width of the paper used and geared so as to work with the general system of cylinders in speed and direction. The disk v^{14} at the working end of the cylinder is cast with a projecting flange, v' , which is cut away at v^2 , Figs. 14 and 18, to permit the addresses to be cut and placed on the sheet of paper as the scroll is drawn from the scroll-spool v^3 .

The scroll-paper should be colored, so as to 15 be readily distinguished in distributing mails, and the addresses printed thereon equidistant, so as to exactly correspond to the distance which the mechanism moves the scroll-sheet at each revolution of the cylinder—say 20 about one-fourth of an inch for each address—and the ratchet movement of the mechanism should exactly correspond thereto.

v^4 is the ratchet-roller, and v^5 is the gumming-cylinder, its gear engaging with that of 25 roller v^4 .

The spool v^3 , Figs. 14 and 16, and the operating mechanism within the flange cylinder-head v , Fig. 16, should not occupy more than two inches longitudinally with the cylinder.

30 The strip of paper containing the addresses being drawn off, the spool v^3 is passed between the gumming-cylinder v^5 and the ratchet-roller v^4 , the printed side of the paper being next to the roller v^4 , from which projects a 35 ratchet-arm having an outward fin or flange, v^6 , to engage the trip-pin v^8 , which permanently projects from the frame. The projection v^7 is a part of and right-angled extension of the arm v^6 , and not only supports and operates the pawl v^9 , that engages with the 40 ratchet, but enables the spring v^{10} to throw the arm v^6 back to position.

The cutter-blades p q , Fig. 15, are serrated, so as not to wear by close shear-cut. One of 45 the blades is bolted to the inside of the projecting rim of the head-piece v' , Figs. 14 and 16, at v^2 , and the other blade to the tilting or movable cutter-piece v^{11} , Fig. 14, and also adjusted to make a close-matched fit, insuring 50 the complete severance of the scroll of paper. The trip shear-arm v^{12} projects so far toward the center of the cylinder as will engage with the trip-pin v^8 , so as to move the cutter-blade to firmly bear on the sheet of newspaper 55 passing between the two addressing cylinders in series A. When the trip projection or arm of the cutter passes the trip-pin, it is thrown back to place by the spring v^{13} .

The small cylinder v^5 , Figs. 14 and 16, is 60 cogged and engaged with the ratchet-roller v^4 , and is made hollow, the outer end being put in by a screw-thread and packed water-tight. A journal should be attached to the head to rest in the bearing affixed to the head-flange, 65 and a journal, v^{20} , should be attached to the end facing the disk v^{14} . This journal should be hollow and funnel-shaped, as it opens into

the gum-fountain v^{15} , Fig. 16. On the working end of the rod v^{17} is a valve, v^{16} , of cork or other substance, sliding in a chamber, v^{21} , 70 having openings near the hollow journal, and this valve may be pressed up to the funnel-opening or drawn off by working the thumb-piece v^{18} , which has a screw and nut for that purpose. This gum-fountain is to be 75 filled with mucilage and sponge to prevent the fluid from slopping, and acts as a reservoir for feeding the small gum-cylinder v^5 . The fountain may be filled from a funnel-opening and corked securely to prevent leak- 80 age.

The small gumming-cylinder v^5 should be 85 perforated with small holes on its cylindrical interior space, filled with sponge and mucilage, and covered firmly with felting or coarse thick cloth, allowing the mucilage to seep through just enough to gum the addresses as they are cut off. The gum-fountain should 90 be made of copper or some non-oxidizing material and form a water-tight union with the gum-cylinder v^5 .

Figs. 11, 12, and 13 represent the construction of the revolving shear-cutters a^{40} , (shown in position in Fig. 1,) in which a^2 is the segment shear-blade, made in two pieces, as seen 95 in Fig. 13, for the purpose of being removed when required—as when the rollers are used for tension only—and without cutting the paper. For this purpose the wheels are made in two parts, to one of which the hub and set-screw are attached, as seen in Figs. 11 and 12, the other part being open in the center to fit over the hub, and between these two parts the circular sections of the steel blades are inserted and made firm by three screw-bolts, 100 as seen in Fig. 11. The faces or cheeks of these two parts should be turned of equal diameter for friction-bearing, and must be recessed to admit the cutter-blade of the engaging cutter-wheel, as seen in Fig. 12, so that 105 each cutter-blade may come to a shear-cut contact, as seen in Fig. 11. To remove the cutter-blades it will only be necessary to loosen the screw-bolts that hold them.

What I claim, and desire to secure by Letters Patent, is—

1. In a combined job and newspaper printing-press, the sets of printing-cylinders, (shown in Figs. 1 and 2,) as B D F, in combination with the alternate sets of reversible printing-cylinders C E G, connected with the intermediate gears, a^3 , as and for the purposes herein described.

2. In a combined job and newspaper printing-press for plain or colored work on one or both sides of the web, a series of ink-fountains, as shown, placed above the printing-cylinders for each set and below each alternate set, provided with means, substantially as herein described, for quick and ready removal and substitution of other fountains containing different colors of ink, in combination with the sets of printing-cylinders, as and for the purposes herein described.

3. In a combined job and newspaper press, for use of different colors on one or both sides of the sheet, the ratchet-arm a^{28} , pivoted to the short connecting-rod a^{28} , which is hinged at a^{22} , in connection with the long connecting-rod a^{24} , that operates the ratchet-arms of the upper ink-fountains, giving reciprocal motion to the connecting-rod a^{31} , which operates the ratchet-arm of the ink-fountain over the reversible set of cylinders G, and also operates the transfer-rollers a^{29} for each of the three ink-fountains as and when the same may be used, two at a time, all in combination, as and for the purposes herein described.
- 15 4. The removable roller-plates b^6 , in combination with the outside frame and reversible cylinders, as and for the purposes herein described.
- 20 5. The inside reversible frames, a^7 , in combination with the type and impression cylinders mounted thereon and the main frame, as and for the purposes herein described.
- 25 6. In a combined job and newspaper printing-press, the reversible inside frame, with its printing-cylinders and trunnions, in combination with the main frame, said frames being provided with bolts and corresponding screw-threaded and free holes made as to exact size and relative position to the center of motion both at top and bottom for interchanging purposes, as set forth.
- 30 7. In combination with the set of reversible type and impression cylinders, the ink-fountains for the same, one above and the other below, with the means for conveying ink from either to the type-cylinder, according to its position, as and for the purposes herein described.
- 35 8. The rock-shaft a^{16} , Fig. 5, provided with cross-arms above and below the reversible cylinder for actuating the reciprocating rollers either at top or bottom, as occasion may require, in combination with the reversible cylinders and the reciprocating rollers, as and for the purposes herein described.
- 40 9. The set of cut-off cylinders a and a^6 , Fig. 5, provided with cutter-bars graduated in distance, as illustrated in Fig. 2 and diagram Fig. 3, having lancet-pointed knives divided in various cross-sections, graded to the minimum width of sheet intended to be slit, and also with other described means to secure cross-cuts in variable lengths, provided also with means, substantially as described, for locking and unlocking the cutter-blades, one or more blades in any section to act upon the web, as may be desired, or one or all save one of the cutting-bars suspended, all in combination, as and for the purposes herein described.
- 45 10. The outside shell of the cylinder a^4 , Fig. 7, consisting of a series of cylindrical segments, k^3 , projecting beyond the line of cross-cut knives, having slots or openings therein sufficient in number and length to admit the knives, in combination with a series of supporting-arms between each series of knives, as and for the purpose herein described.
- 50 11. The cylinder provided with projecting shell and annular projections k , Fig. 8, in combination with the guide-rods k' , cutter-bar, with its removable section-knives, and roller-bar, as and for the purposes herein described.
- 55 12. The cutter of the cut-off cylinder, in combination with the spiral springs, the guide-rods, stop-off fork, and stop-off pin, as and for the purposes herein described.
- 60 13. The cut-off knives provided with spiral springs, the stop-off pins, the stop-off forks, and the supporting-arms, all in combination with the cut-off cylinders a and a^4 , as and for the purposes herein described.
- 65 14. The guide-rods k' , the spiral springs k^2 , tilting rod l' , cutter-bar, with its removable section-knives, and roller-bar k^5 , and riser-cam k^7 , all in combination, as and for the purposes herein described.
- 70 15. The series of cut-off knives provided with round holes in their longitudinal centers, with openings to the backs of the same, as shown in Figs. 9 and 10, in combination with the large headed bolts having cut-away shanks, as shown in Fig. 18, the cutter-bar m , and the slitting-shears a^{10} , Fig. 1, as and for the purposes herein described.
- 75 16. In a combined job and newspaper printing-press using cylindrical plates, a cylinder provided with disk and flange at its working end, containing a scroll-spool, v^8 , Figs. 14 and 16, a perforated gum-cylinder, v^5 , in contact with roller v^4 , acting upon the scroll-web, the serrated knives P, and with means to operate the whole, as shown in Figs. 14, 15, and 16, all in combination, as and for the purposes herein described.
- 80 17. In a combined job, newspaper, and addressing printing-machine, the perforated gum-cylinder v^5 , provided with cloth covering and with means of communicating with the reservoir v^{15} , and also provided with means (as the valve v^{16}) to regulate the supply of liquid gumming material, in combination with the gum-fountain v^{15} , the contact-roller v^4 , arm v^6 , and the trip-pin v^8 , as and for the purposes herein described.
- 85 18. The revolving shear-cutters, Figs. 11, 12, 13, (a^{10} in Fig. 1,) provided with semicircular shear-blades; Fig. 13, removable at pleasure, and also provided with flanges or cheeks each side of the cutting-blade for friction-tension with the web on the line of cut, all in combination and in combination with the cut-off knives in the cut-off cylinder, as and for the purposes herein described.
- 90 19. The trip-pin v^8 , Figs. 14 and 15, in combination with the frame f , the trip shear-arm v^{12} to cutting-blade p , and arm v^6 , and roller v^4 , operated thereby, as and for the purposes herein described.
- 95 20. The form and impression cylinders and the ink-fountains provided with adjustable

means for printing one or both sides of the web in one or more colors at one operation, and jobs of various widths and lengths at one operation, substantially as herein described, 5 in combination with the revolving shears and the cut-off knives, as and for purposes herein described.

21. A series of stationary printing-cylinders in a web-feeding printing-press, in combination with a series of alternate sets of reversible form and impression cylinders, and in combination with changeable ink-fountains for change and proper distribution of colors, so constructed and fitted to the frame 15 that any one of any color may be displaced and another of another color substituted therefor, as and for the purposes herein described.

22. The type-cylinders provided with the longitudinal markings and numberings, in combination with the cut-off knives, as and for the purposes herein described.

23. The type-cylinders provided with the circumferential markings and numberings, in

combination with the slitting-shears and the 25 cut-off cutter-bars and series of cut-off knives, as and for the purposes herein described.

24. The cut-off cylinder a^4 , Fig. 1, provided with a slotted shell bolted to a series of arms, k^6 , corresponding in number to the series of 30 cut-off knives projecting beyond the line of web and knives, in combination with the guide-rods and cross-cutting knives, as and for the purposes herein described.

25. The cylinder a^4 in series A, provided 35 with gum-fountain, cylinder v^5 , gum-reservoir v^{15} , Fig. 14, and connecting mechanism, substantially as described, for addressing subscribers' names on the margin of newspapers, in combination with cylinder a in series A, 40 as and for the purposes herein described.

In testimony whereof I affix my signature in presence of two witnesses.

STEPHEN D. CARPENTER.
